UNITED STATES PATENT OFFICE.

ANNE COLLINS BERRY, OF RICHMOND HILL, NEW YORK

CHILD'S AND LADY'S GARMENT.

1,369,761.

Specification of Letters Patent. Patented Feb. 22, 1921.

Application filed February 29, 1916, Serial No. 81,297. Renewed July 20, 1920. Serial No. 397,705.

To all whom it may concern:

Be it known that I, ANNE COLLINS BERRY, a citizen of the United States, and resident of Richmond Hill, county of Queens, State of New York, have invented certain new and useful Improvements in Children's and Ladies' Garments, of which the following is a specification.

This invention relates to union garments in the form of an outside piece of apparel or a piece of underwear, a night-dress or the like, and the invention has to deal particularly with the portion of the garment covering the body from the waist down to the knees, and embodies essentially a novel pattern of skirt and bloomer legs so designed that a neatly appearing garment is produced with a minimum of material and without bulkiness at the bloomer legs, whereby comfort and freedom of motion is obtained, as well as the proper set of the skirt. The new combination of bloomer legs and skirt lends itself to a variety of forms of garments and the bottom of the skirt can be finished with a hem, tuck or flounce, or made without a hem, tuck or flounce, in which case the bottom of the skirt will hang gracefully as if the skirt were cut from an ordinary pattern without bloomer legs attached.

For a more complete understanding of the invention reference is to be had to the following description and claims taken in connection with the accompanying drawing, which illustrates certain embodiments of the invention and wherein similar characters of reference indicate corresponding parts in all the views, in which—

Fig. 1 is a perspective view of a dress shown on the figure of a child;

Fig. 2 is a front view of the dress spread out flat;

Fig. 3 is a side view of the dress as when it is on a child;

Fig. 4 is an enlarged vertical section of the lower portion of the garment;

Fig. 5 is a plan view of the front or rear section of the union garment shown in Fig. 1;

Fig. 6 is a view showing the straight pieces forming the placket between the leg holes;

Fig. 7 is a view showing a combined skirt and bloomer garment;

Fig. 8 is a plan view of one of the sections from which the garment shown in Fig. 7 is made;

Fig. 9 is a view of an under garment with a flounce extending around the bottom thereof; and

Fig. 10 is a view of an under garment without a flounce, hem or tuck.

It is to be understood that the invention, which relates to the lower part of a garment and bloomer legs combined therewith, can be embodied as a dress, as shown in Fig. 1, a skirt garment, as shown in Fig. 2, or as an under garment, as shown in Figs. 9 and 10, and furthermore, the invention can be embodied as a bathing suit, night-dress, etc.

Referring to Figs. 1 to 5 inclusive, the garment A is preferably composed of front and rear sections 1 and 2, each of which may be made from a single piece of goods or a plurality of pieces sewed together. Each section embodies a skirt portion 3, which has lateral edges 4 that diverge downwardly from the armpits in the type of garment shown in Fig. 1, or from the waist in the type shown in Fig. 7, and below the bottom of the skirt portion, indicated by the dotted line 5, the garment section continues into the portion 6 that forms the front or rear portion of the bloomers. The bloomer portion 6 has its side edges 7 converging downwardly from the line 5 to the points 8, from which the edges of the bloomer portions converge abruptly to the points 9. The converging edges 7 of the two sections are sewed together to form the side seams of the bloomer legs, and the edges 4 of the sections are sewed together to complete the skirt. The abruptly converging edges 10 are not sewed together, so as to form the leg openings of the garment. The edges 10 are folded back along the lines 11 into hems for receiving an elastic or draw string 12, as shown in Fig. 4, whereby the bloomer legs can be snugly fitted around the limbs of the wearer, or, if desired, the legs can be left free or open, which is especially desirable in the case of drawers. The part 13 between the leg openings 14 constitutes a placket. To form this placket the front and rear sections may have a central inverted V-shaped recess 13 cut therein, although this particular shape is not absolutely necessary. Along the edges of the recess 13 or the portion between the leg openings each section of the garment has sewed thereto straight pieces of goods 15. These straight pieces afford

an adequate foundation for buttons and buttonholes, whereby the part of the garment between the legs can be buttoned and unbuttoned. In a union garment constructed in the manner disclosed the leg openings are close together and there will be a minimum bulk of material between the legs of the wearer, and furthermore, the outer portions of the leg openings will lie 10 inwardly from the bottom edge of the skirt, which will hang in a fold on the circular line 5. The graceful hang of the skirt portion of the garment is obtained by the front and rear sections being of greatest length 15 at the center, by the rear section being slightly longer than the front section, according to the size of the wearer, and by the side portions of the bloomer legs converging downwardly. The garment may 20 be made with a hem around the bottom of the skirt, in which case the bloomer legs are folded upwardly into the skirt on the curved line 5, and the skirt and bloomer portions are sewed together by a line of 25 stitching 16 parallel with the line of fold 5. In this case, as shown in Figs. 1 to 3, the circular hem or tuck 17 thus formed overhangs the bloomer legs. In addition to the hem, a ruffle or flounce 17', as shown in 30 Fig. 9, can be sewed to the bottom of the skirt. It is to be understood that a hem is not essential to impart to the garment a proper skirt effect, as will be seen from Fig. 10. When a hem is employed the same 35 can be "let out" or made narrower from time to time in order to lengthen the garment as the wearer grows.

I claim:

1. A union garment comprising a skirt flaring downwardly and bloomer legs connected with the bottom portion of the skirt, there being a placket extending from the inner side of one leg opening to the inner side of the other leg opening, and fasteners 40 for closing the placket, said garment being made of similar front and back sections and each having the side edges of the skirt and bloomer portions sewed together, the 45

sections being folded on a curved line and sewed to form a circular tuck or hem at the 50 bottom of the garment which overhangs the bloomer legs, the legs of the garment being so constructed that when the garment is worn the legs cover the bottom space of the skirt and fasten around the wearer's limbs. 55

2. A garment designed to be worn without petticoats or drawers and including legs having a placket extending from the bottom edge of one leg to the crotch and from the crotch to the bottom edge of the other leg, strips 60 of straight material stitched along the edges of the placket, and fastening means on the strips for closing the placket, the legs of the garment being so constructed that when the garment is worn the legs hang down 65 from the skirt portion with the lower ends of the legs fastened around the wearer's legs above the knees.

3. A union garment designed to be worn without petticoats or drawers, the same 70 comprising a skirt flaring downwardly and bloomer legs connected with the bottom portion of the skirt, there being a placket extending from the inner side of one leg opening to the inner side of the other leg opening, and fasteners for closing the placket, 75 said garment being made of similar front and back sections sewed together and each having the side edges of the skirt portion diverging downwardly and the side edges 80 of the bloomer leg portion converging downwardly, the sections being folded on a curved line and sewed to form a circular tuck or hem at the bottom of the garment which overhangs the bloomer legs, the legs 85 of the garment being so constructed that when the garment is worn the legs hang down from the skirt portion with the lower ends of the legs fastened around the wearer's legs above the knees. 90

I hereby affirm that the above is correct.

ANNE COLLINS BERRY.
